Filed Feb. 26, 1923

Inventor

BENJAMIN M. FRANK

By his Attorney Chat. C. Gill

UNITED STATES PATENT OFFICE.

BENJAMIN M. FRANK, OF NEW YORK, N. Y., ASSIGNOR TO GREENPOINT METALLIC BED CO., INC., OF BROOKLYN, NEW YORK, A CORPORATION OF NEW YORK.

DESIGN FOR AN ORNAMENT FOR BEDSTEAD FRAMES.

Application filed February 26, 1923. Serial No. 5,291. Term of patent 3½ years.

To all whom it may concern:

Be it known that I, BENJAMIN M. FRANK, a citizen of the United States, residing at New York city, in the county and State of New York, have invented a new, original, and ornamental Design for an Ornament for Bedstead Frames, of which the following is a specification, reference being had to the accompanying drawings, forming a part thereof, and in which is shown a front elevation of an ornament for bedstead frames embodying my design.

I claim:

The ornamental design for an ornament for bedstead frames, as shown.

BENJAMIN M. FRANK.
